[57] **CLAIM**

The ornamental design for a padlock casing, as shown and described.

DESCRIPTION

FIG. 1 is a perspective view of the padlock casing of the present invention in the closed configuration;

FIG. 2 is a perspective view thereof in the open configuration, the broken line showing of a hasp, staple and padlock being for illustrative purposes only and forming no part of the claimed design;

FIG. 3 is a perspective view of the rear portion thereof with the front portion omitted for clarity and with the broken line showing of the staple plate and staple retaining the padlock casing in place being for illustrative purposes only and forming no part of the claimed design; and,

FIG. 4 is a front view of the rear portion thereof, the rear view identical.
